DELIVERY FOR TOBACCO STRIPPERS

Rupert E. Rundell, Rockville Centre, N. Y., assignor to International Cigar Machinery Company, a corporation of New Jersey

Application November 30, 1937, Serial No. 177,216

24 Claims. (Cl. 131—124)

This invention relates to stemming and/or stripping and booking of tobacco, more particularly to delivery mechanisms for stemming machines. The main object of the invention is to improve prior types of delivery mechanisms so that laying of the stemmed tobacco leaves in out-spread condition may be assured. To this end the stemmed leaves are delivered between traveling endless belts which have opposed runs coacting to grip and advance the leaves, and having their delivery ends mounted on swinging members which cause the belts to swing to and fro while delivering the leaves on to a flat surface.

A further object of the invention is to segregate unstemmed or incompletely stemmed leaves. For this purpose there may be employed a revolving brush or the like which transfers leaves from the stemming machine to the said belts and which may be controlled by a defective leaf detector so that it will be moved out of operative position at the time an unstemmed or incompletely stemmed leaf reaches transferring position.

Still another object is to provide a delivery mechanism wherein various lengths of leaves may be handled and deposited in the desired relationship, upon merely advancing or retarding the swinging movement of the members over which the exit ends of the delivery belts are guided. Another objective is to deposit the stemmed leaves on a traveling screen in successively overlapping pairs having an end-to-end relationship or in a single row thereon upon substitution of the appropriate change gear. The traversing crank-gear traversing the swinging members to and fro across the screen may be timed to reach the limits of its throw while the tips of successive leaves are emerging from between the delivery belts, wherefore the leaves will be deposited in butt-to-butt relationship on the screen. Upon relatively displacing the crank-gear a quarter-turn, the leaves will be laid tip-to-tip, which is preferred. Substitution of the appropriate size of change gear for driving the crank-gear will permit the leaves to be deposited in a single overlapping row on a traveling screen, or in a booked, that is, a stacked relationship on a stationary screen.

In the accompanying drawings which form a part of this specification and in which like characters of reference indicate the same or like parts:

Fig. 1 is a side elevation of one embodiment of the delivery mechanism in conjunction with the delivery end of a stemming machine;

Fig. 2 is an end view of the same;

Fig. 3 is a detail view of the same shown on an enlarged scale;

Fig. 4 is a diagrammatic view of a portion of the delivery mechanism shown in Fig. 3, operating to advance a stemmed leaf;

Fig. 5 is a diagrammatic view of the same, operating to eject an unstemmed or incompletely stemmed leaf;

Fig. 6 is a schematic view illustrating the operation of the delivery mechanism in laying leaves tip-to-tip on a traveling screen;

Fig. 7 is a plan view showing the arrangement of a number of stripping machines delivering the stemmed leaves in tip-to-tip relation on to screens placed on the conveyor belt;

Fig. 8 is a detail view of one of the screens showing the delivery of a single row of leaves thereon;

Fig. 9 is a detail view of one of the screens showing the leaves placed in butt-to-butt relation thereon;

Fig. 10 is a diagrammatic side elevation of the stripping mechanism of a stemming machine provided with members for advancing and transferring the stemmed leaves to the delivery mechanism; and

Fig. 11 is a detail section of the gear wheel and solenoid-actuated pins of the detector device.

Referring to the drawings, the delivery mechanism illustrated may be used in conjunction with a stemming machine of the general type shown in Patent No. 1,981,470, granted to R. E. Rundell et al., November 20, 1934. In the machine illustrated therein the stemmed leaves are delivered tip first by driven belts 10 and 11 (Figs. 1 and 3) which coact to grip and advance the leaves over a revolving brush 12 acting to guide them to a pair of belts 13 and 14 coacting to grip and forward the leaves between them. The belts 13 and 14 pass over idler rollers 15 and 16, respectively, and travel in an upward direction over a driving drum 17 and thence over a guide roller 18 directing them downwardly over idler rollers 19 and 20 respectively. The belt 13 is thence led upwardly over idler rollers 21 and 22 and back over a tightener roller 23 to the roller 15, and belt 14 is led upwardly and back over a tightener roller 24 to roller 16.

Rollers 15 and 16 are supported at their ends in bars 25 suspended from side frames 26 and 27 wherein are also supported the shaft 28 of drum 17 and the rollers 21 and 22. Roller 23 is mounted on a cross shaft 29 journaled in one end of bell-crank levers mounted on studs 31 carried by the side frames. To the other end of levers 30 are connected springs 32 anchored to posts 33 secured in the side frames which urge the roller 23 into position to keep the belt 13 taut. Belt 14 is kept taut in a like manner by means of springs 34 urging upwardly the arms 35 clamped to pivot shafts 36 supported in side frames 26 and 27. Said frames are supported by brackets 37 carried by the inclined channel-bars 38 of the stemming machine and at their lower ends are connected by tie bars 39.

The rollers 19 and 20 of belts 13 and 14 are mounted in swinging arms 40 and 41 carried on a shaft 42 journaled in the side frames 26 and 27. The swinging motion of arms 40 and 41 is derived from gears 43 and 44, the former being driven from the stemming machine by a sprocket chain (not shown) and driving gear 44 which is equipped with a crank pin 45 engaging the bearings 46 in one end of a connecting rod 47 whose other end is pivoted on a wrist-pin 48 carried by the lever 49. At its upper end the lever 49 is clamped to a rocker-shaft 50 which is supported in frames 26 and 27 and carries at its other end an arm 51. A forked head 52 fastened to the lower ends of arms 49 and 51 carries rods 53 connected by eyes 54 to studs 55 of arms 40 and 41. A plate 60 having flanges 61 secured to the inner walls of arms 40 and 41 engages the inner loop of belt 14, and the longitudinal strips 62 carried by straps 63 secured to the inner faces of arms 40 and 41 engage the inner loop of belt 13, thus preventing sagging of the same and slipping of the leaves carried downwardly between said belts.

The swinging arms 40 and 41 sweep the exit ends of the belts 13 and 14 from position 64 to position 65 indicated in dotted lines (Fig. 6) above a screen 66 on which the leaves are to be delivered and serve to deliver the leaves tip first and lay them in outspread condition in the particular relationship desired. Laying the leaves in a tip-to-tip relation is the preferred way and to obtain this result the radius of the crank pin 45 with respect to the center of gear 44 is sufficient to swing the arms 40 and 41 across the width of the screen and the linear speed of the belts 13 and 14 is such that the crank pin reaches a position intermediate the limits of its throw while the tip of the leaf is emerging from their exit ends. The particular gear ratio selected for gears 43 and 44 is 2 to 1, but any suitable ratio may be used. Therefore during the forward swing of the arms 40 and 41 the emerging tip end of the leaf will be laid on the screen slightly before it reaches the center of said screen, and the continued forward movement of the arms 40 and 41 causes the leaf to be spread over the remainder of the screen. On the return stroke of arms 40 and 41, the succeeding leaf will be laid in the opposite direction with its tip end overlapping the tip of the leaf previously delivered on to the screen and the screen may be continuously advanced to cause overlapping of successive pairs of leaves.

To deliver the leaves in a butt-to-butt fashion, Fig. 9, the gear 44 is adjusted by disengaging the gear 43 therefrom and turning gear 44 one quarter-turn and then reengaging the gear 43 therewith, so that the laying of the leaf will be started with the tip end adjacent either side of the screen and continued until the butt end of the leaf L extends across the center of the screen, the movement of the arms spreading the leaf over the screen. On the return stroke of the arms, the next leaf will be laid in the same manner, with its butt end overlapping the previously laid leaf, and the screen may be advanced continuously to obtain the illustrated lateral overlapping of the leaves.

A number of machines A, B, C, etc., may be arranged as indicated in Fig. 7, to lay the leaves in tip-to-tip relation as shown, or butt-to-butt or other desired relation, the delivery mechanism of each machine delivering a different kind or grade of tobacco leaves on to the screens 66 which are advanced on an endless conveyor belt

67 at a speed slow enough to cause overlapping of successive pairs of leaves. In this manner, the different grades of tobacco will be blended on the screens. Thus if five parts of one grade of tobacco are to be blended with two parts of a second kind and with one part of a third kind, eight machines will be required, five of which handle the first kind of tobacco, two handling the second kind, and one the third kind. When the screens have passed all of the machines they arrive at the end of the conveyor and are lifted therefrom and transported to a drying chamber where the blended tobacco is permitted to dry before being placed in a storage bin. My pending application, Serial No. 60,808, filed January 25, 1936, which issued as Patent No. 2,195,427 on April 2, 1940, has a continuation in part in this application as to the blending.

To lay a single row of overlapping leaves as seen in Fig. 8, the gearing 43-44 is replaced by a crank-gear having half the throw of gear 44 and a pinion which will give a 1 to 1 ratio with the crank gear. Therefore a leaf will be fed only during the forward stroke of the arms and the return stroke will be completed without delivering a leaf. The screen will be advanced at the appropriate speed to obtain the desired overlapping of the leaves. With a stationary screen the leaves will be deposited in stacked or booked relationship.

If during the operation of the machine a leaf should reach the delivery mechanism unstemmed or only partially stemmed, a control mechanism of the general type disclosed in Patent No. 2,019,721, granted to P. M. Nejedly, dated November 5, 1935, will swing lever 70 (Fig. 3) and through its connections to the brush 12 move the same to its dotted position 71. This permits the leaf to be advanced away from the pick-up belts 13 and 14 to the lowered position 71 of brush 12 and thereby rejected. Lever 70 is connected by a link 72 to a bell crank lever 73 clamped on one protruding end of a cross shaft 74 supported in the brackets 75 of the machine, the other end of shaft 74 carrying a crank 76. Cranks 73 and 76 each carry eyes 77 connected by turn-buckles 78 to eyes 79 pivotally secured to arms 80. The cross-shaft 81 on which the brush 12 is mounted is supported in the ends 50 of the arms 80 which are loosely mounted on a sleeve 82 supported on a shaft 83 carried by brackets 75.

Arms 84 attached to each end of a rod 85 carried by bracket 75 support a cross-shaft 86 on which is mounted a brush 87 arranged to engage belt 11 and wipe off any clinging leaves from the same. The brush 89 carried by bars 49 and 46 (Fig. 1) and driven from the shaft of pulley 19 coacts with the belt 14 in the same manner. A sprocket 88 fixed on the shaft 86 which is suitably driven from the stemming machine, drives a chain 89 running over an idler sprocket 90 loosely mounted on the sleeve 82. A gear 91, which may be integral with or fastened to sprocket 90, meshes with a gear 92 attached to the brush shaft 81. Bars 93 fastened to the brackets 75 support each of the side frames 26 and 27, and are equipped with cross members 94 which engage belts 13 and 14 and prevent sagging thereof. Straps 95 which support the lower ends of the bars 25 are also provided on the bars 93.

It may be noted that with the present delivery mechanism a wide range of various lengths of leaves may be handled, provided the maximum

length does not exceed the throw of the swinging arms, and deposited in the desired end-to-end or stacked relationship, upon the appropriate adjustment of the crank-gear relatively to its driving pinion 43 to advance or retard the swinging movement of the exit end of the delivery belts relative to the stemming machine with which the delivery mechanism is associated.

In Fig. 10, certain details are shown of the particular stemming machine referred to above to illustrate the invention wherein the leaves enter tip first between opposed vertical runs of the endless belts 100 and 101 whereby they are delivered on to the rotating suction drum 102 to which the successive leaves adhere while their stems are seized and torn out by grippers (not shown), of the gripper drum 103. The leaves are delivered by the suction drum to an endless conveyor belt 104 serving to transport them to the delivery belts 10 and 11. On the belt 104 the leaves are advanced under a detector (not shown) of control mechanism illustrated in the above-mentioned Nejedly patent, whereby the link 70 is actuated to swing the brush 12 into position to divert unstemmed and incompletely stemmed leaves.

For this purpose the arm 171 of lever 70 extends into the proximity of the path of the axially displaceable pins 172 mounted in the web of the gear wheel 173 revolving on the shaft 174. Gear 173 is suitably driven from the main drive of the stemming machine. A solenoid 175 has a core 176 connected to one arm of a three-arm lever 177 fulcrumed on a bracket 178. The lower arm of lever 177 is provided with an arcuate flange 179 coextensive with a portion of the path of pins 172, which is normally held out of contact with the pins by the tension spring 180 connected to the upper arm of the lever. Upon energization of the solenoid 175, due to the detection of an unstemmed or partially stemmed leaf on the belt 104, as described in the Nejedly patent, the flange 179 of the lever is swung against the particular pin 172 then opposite it, so that it will be displaced sufficiently to engage and actuate the arm 171 when the detected leaf has reached the brush 12. The arm 80 carrying the latter is rocked sufficiently to move the brush into a position which permits diversion of the defective leaf. A tension spring 181 suitably connected to the linkage actuating the arm 80 normally maintains the brush 12 in its operative position and at the same time yieldingly urges the arm 171 into the path of the axially displaced pin. The latter is returned to its initial position upon engaging a stationary cam plate 182.

What is claimed is:

1. The combination with a screen, of a traveling member adapted to advance the screen horizontally, a plurality of mechanisms receiving a desired variety of grades of stemmed tobacco to form a blend and depositing them so that they will be deposited to assume a paired relationship extending transversely of the advancing screen with successive pairs of leaves overlapping each other laterally.

2. The combination with means for removing the stems of tobacco leaves, of mechanism for advancing the stemmed leaves from said means, and spreading and laying them in booked relationship, said mechanism including a pair of endless traveling belts arranged to admit therebetween stemmed leaves from said means and coacting to advance and deliver the leaves edgewise, and pendant swinging members over which

said belts are guided to provide opposed runs coacting to deliver the leaves in booked relationship and spread the same during delivery.

3. The combination with means for stemming tobacco, of delivery mechanism for receiving the stemmed leaves from said means, said mechanism including a pair of endless traveling belts arranged to admit therebetween stemmed leaves from said means and coacting to advance and deliver the leaves edgewise, and pendant swinging members over which said belts are guided to provide opposed runs coacting to deliver the leaves, and a device for traversing said members to and fro to deliver the leaves in a paired relationship and cause spreading of the leaves during delivery, said device being adjustable to cause each pair of leaves to be deposited with their tips or their butt ends adjacent each other and their other ends remote from each other.
4. Mechanism for depositing tobacco leaves in outspread fashion comprising a pair of endless traveling belts having opposed runs arranged to admit the leaves therebetween and coacting to advance and deliver the leaves edgewise, and pendant swinging members over which said belts are guided to provide opposed runs coacting to deliver the leaves and spread the same during delivery.
5. Mechanism for depositing tobacco leaves in outspread fashion comprising a pair of endless traveling belts arranged to admit tobacco leaves therebetween and coacting to advance and deliver the leaves edgewise, pendant swinging members over which said belts are guided to provide opposed runs coacting to deliver the leaves, and a device connected to said members and swinging them to and fro in a direction to cause spreading of the leaves during delivery.
6. Mechanism for depositing tobacco leaves in outspread fashion comprising a pair of endless traveling belts arranged to admit tobacco therebetween and coacting to advance and deliver the leaves edgewise, pendant swinging members, rollers carried by said members over which said belts are guided to provide opposed runs coacting to deliver the leaves vertically, and a device connected to said members for swinging them to and fro to spread and lay the leaves so that they will be deposited to assume a paired relationship having a tip-to-tip relationship.
7. Mechanism for depositing tobacco leaves in outspread fashion comprising a pair of endless traveling belts arranged to admit tobacco leaves therebetween and coacting to advance and deliver the leaves edgewise, pendant swinging members, rollers carried by said members over which said belts are guided to provide opposed runs coacting to deliver the leaves vertically, and a device connected to said members for swinging them to and fro in properly timed relation to spread and lay the leaves so that they will be deposited to assume a paired relationship having a butt-to-butt relationship.
8. Mechanism for depositing tobacco leaves in outspread fashion, comprising a pair of endless traveling belts arranged to admit tobacco leaves tip first therebetween and coacting to advance and deliver the leaves edgewise, pendant swinging members, rollers carried by said members over which said belts are guided to provide opposed runs coacting to deliver the leaves vertically, and a device connected to said members for swinging them to and fro to spread and lay the leaves with their tips pointing in the same direction.

9. Mechanism for depositing tobacco leaves in outspread fashion, comprising a pair of endless traveling belts arranged to admit tobacco therebetween and coacting to advance and deliver the leaves edgewise, pendant swinging members, rollers carried by said members over which said belts are guided to provide opposed runs coacting to deliver the leaves vertically, and a device connected to said members and swinging them to and fro in properly timed relation to spread and lay the leaves in booked relationship.

10. The combination with an endless traveling member arranged to receive stemmed leaves from a stemming machine and advance the same, and mechanism for swinging said member to and fro to deliver the stemmed leaves in outspread condition.

11. The combination with an endless traveling member arranged to receive stemmed leaves from a stemming machine and advance the same, and mechanism for swinging said member to and fro to deliver the stemmed leaves in outspread condition, said mechanism being adjustable to advance or retard the swinging movement of said member relative to said machine and thereby deliver leaves of various lengths in a predetermined relationship.

12. Mechanism for depositing tobacco leaves in outspread fashion, comprising a pair of endless traveling belts arranged to admit tobacco leaves therebetween and coacting to advance and deliver the leaves edgewise, pendant swinging members over which said belts are guided to provide runs coacting to deliver the leaves, and a device connected to said members for swinging them to and fro in a direction to cause spreading of the leaves during delivery, said device being adjustable to advance or delay the swinging movement of said members and thereby deliver leaves of various lengths in a predetermined relationship.

13. The combination with an endless traveling member arranged to receive tobacco leaves and advance and deliver them edgewise, of a device for traversing said member to and fro in a direction to cause spreading of the leaves during delivery.

14. The combination with means for delivering stemmed tobacco leaves, of a revolving roll, and mechanism for swinging said roll away from its operative position to cause diversion of imperfectly stemmed leaves away from said means.

15. In a stemming machine, the combination with a plurality of leaf blending screens, of a continuously traveling conveyor adapted to detachably support in a substantially continuous series a plurality of the leaf blending screens and advance the same horizontally of a stripped leaf delivering means extending transversely of the direction of movement of said screens, said means including traveling conveyor belts moving transversely of said screens for delivering the stripped leaves on to said screens with their lengths extending transversely thereof during the continued movement of the screens.

16. In a stemming machine, the combination with means for continuously advancing stemmed tobacco leaves endwise in an outspread condition, of opposed members arranged to admit the stemmed leaves endwise therebetween while they are being continuously advanced by said means and coacting to grip and advance said leaves and deposit them in outspread condition.

17. In a stemming machine, the combination with means for continuously advancing stemmed

18. In a stemming machine, the combination with means for continuously advancing stemmed tobacco leaves endwise in an outspread condition, of opposed members arranged to admit the stemmed leaves endwise therebetween while they are being continuously advanced by said means and coacting to grip and advance said leaves and deposit them in outspread condition, and a device for actuating said members to deposit said leaves in booked relationship.

19. In a stemming machine, the combination with means for continuously advancing stemmed tobacco leaves endwise in an outspread condition, of opposed members arranged to admit the stemmed leaves endwise therebetween while they are being continuously advanced by said means and coacting to grip and advance said leaves and deposit them in outspread condition, and a device for actuating said members to deposit the leaves in a paired relationship.

20. In a stemming machine, the combination with means for continuously advancing stemmed tobacco leaves endwise in an outspread condition, of opposed members arranged to admit the stemmed leaves endwise therebetween while they are being continuously advanced by said means and coacting to grip and advance said leaves and deposit them in outspread condition, and a device for actuating said members to deposit the leaves in a paired relationship, with the leaves of each pair overlapping at one end and remote from each other at their other ends.

21. The combination with a screen, of a traveling member adapted to advance the screen horizontally, a plurality of mechanisms for receiving stemmed tobacco leaves in outspread condition and laying them outspread in a paired relationship on said screen and extending transversely thereof with similar ends overlapping.

22. The combination with a screen, of a traveling member for advancing said screen horizontally, and opposed members arranged to admit the stemmed leaves endwise therebetween while they are being advanced by said means and coacting to grip and advance said leaves and deposit them in outspread condition on said screen extending transversely thereof and in laterally overlapping relationship thereon.

23. The combination with means for stemming tobacco leaves, of opposed traveling members arranged to grip the stemmed leaves therebetween and advance them endwise and deposit them in outspread booked relationship.

24. In a stemming machine, the combination with mechanism for delivering stemmed tobacco leaves, of means operating to advance stemmed tobacco leaves edgewise into said mechanism, and a device for bodily moving said means away from operative position to cause diversion of imperfectly stemmed leaves away from said mechanism.
